INTERNAL COMBUSTION ENGINE OIL RECTIFYING SYSTEM

Filed June 15, 1925

UNITED STATES PATENT OFFICE.

RALPH L. SKINNER, OF DETROIT, MICHIGAN, ASSIGNOR TO SKINNER AUTOMOTIVE DEVICE CO., INC., OF DETROIT, MICHIGAN, A CORPORATION OF CALIFORNIA.

INTERNAL-COMBUSTION-ENGINE OIL-RECTIFYING SYSTEM.

Application filed June 15, 1925. Serial No. 37,157.

My invention pertains to features of novelty in the systems employed in association with internal-combustion engines which purify the lubricating oil, or which prevent it from becoming contaminated, or which accomplish both results more or less conjointly.

One object of the present invention is to provide an apparatus or system of this general character which will withdraw the aerated lubricant substantially continuously from the engine, preferably from around the pistons and desirably from their piston-ring grooves, and which will return the reclaimed or purified oil practically continually to the lubricating system of the engine.

Another purpose of the invention is the provision of a system of this or similar character which does not employ any floats or any valves likely to become fouled or rendered inoperative by reason of the presence of carbon or dirt in the oil undergoing treatment.

A further aim of the invention is to supply an appliance of this type wherein the refinement of the impure oil, to free it from its volatile constituents, occurs in a chamber subjected to subatmospheric pressure and also preferably to heat, a pump or equivalent appliance being employed to return the purified oil back to the lubricating system, as, for instance, the engine crank-case, under atmospheric pressure but without substantial capacity for pumping back any material amount of air or gases.

An added feature of the new construction is the use of a check-valve or similar device to prevent oil or air from entering the separating chamber through the discharge or delivery pipe.

Still a further novelty in the structure is the use of a thermostatically-controlled valve so located and arranged that if it does not always function properly, it will have no substantially detrimental effect on the action of the appliance as a whole, such thermostat controlling the action of the heat on the fluids undergoing treatment.

Various other features of novelty and improvement will be made apparent from a detailed understanding of the preferred embodiment of the invention illustrated in the accompanying drawings throughout the several views of which like reference characters have been used to designate the same parts.

In these drawings:

Figure 1 is a fragmentary vertical section

of the construction, illustrating its manner of operating;

Figure 2 is a fragmentary horizontal section through the heating portion of the rectifier;

Figure 3 is an enlarged horizontal section on line 3—3 of Figure 1; and

Figure 4 is an enlarged fragmentary plan view of the means employed to adjust the amount of heat to which the separator is subjected.

In this structure, which depicts only one cylinder of a multi-cylinder internal-combustion engine having any approved style of lubrication system, the engine cylinder 110, 70 water-cooled at its upper portion, accommodates the usual reciprocating piston 111 and the latter has an extension 112 on its skirt in alignment with a port 113 through the cylinder side wall, the piston having a plurality of piston-ring grooves 114, 115 and 116 and their corresponding piston-rings 117, 118 and 119, the lower groove 116, inwardly of its ring, being joined to a lengthwise groove 121 on the surface of the piston in 75 register with the cylinder port 113, such lower groove opposite the port having an air-inlet port 112 extended inwardly through the piston wall to the hollow interior thereof which is in direct connection with the interior 80 of the crank-case.

This is a known construction as presented in my United States Patent No. 1,502,922, internal-combustion engine construction, granted July 29, 1924.

Port 113 is joined by a pipe 123 to a right-angle passage 124 in the casting 125, an adjacent right-angle passage 126 in such casting connecting with a pipe 127 joined to the intake-manifold of the engine as a source of 95 suction.

This casting 125 is covered by a shell or casting 128 secured thereto around its periphery by a plurality of screws 129 and forming therewith a separation or distillation chamber characterized 130.

Such member 128 is housed within and inwardly spaced from an outer shell 131 of the shape shown in the drawings and having an inturned, lower, marginal, circular flange 132 engaging the outer face of the inner shell, the element 131 being fastened by screws 132, or in any other convenient manner, to the laterally-apertured exhaust-manifold 120 of the engine, whereby the hot exhaust gases or 110

a portion of them may flow through the space between the two shells and heat the contents of chamber 130 as will be readily understood.

In order to prevent a direct play of such hot gases on the inner shell 128, a curved deflector 133 forms a part of the outer casing member and directs the gases around the annular or arcuate space between the nested shells.

10 To control the heating effect, a hinged valve 134 is provided, the hinge-pin 135 thereof in the member 131 having a slotted plate 136 fastened thereto above the casing with a securing screw 137 extended through its curved slot and taking into the element 131, whereby the degree of opening or closing of the valve may be easily brought about and the valve maintained in adjusted position.

Thus the distillation or refinement chamber 20 may be heated in adequate or proper degree by the heat developed by the engine itself.

In some localities a substantial amount of heat will be needed to accomplish the best results and in other places possibly no heat at 25 all will be required.

30 A cup 141 is secured centrally on the top of the casting 125 by means of a hollow threaded connector 142 extended through a central hole in the bottom of the cup into the upper end of the passage 126, the upright section of which is in the center of the casting as is clearly illustrated.

35 An inverted, apertured, shallow, cup deflector 143 is interposed between the bottom wall of cup 141 and the top face of the casting, the connector 142 extending through such intermediate member as is fully shown.

40 A central stand-pipe 144 is mounted on the connector and its upper end is surrounded by a larger, inverted, cup-shaped deflector 145 carried on the under face of the top wall of shell 128.

45 An upright vent pipe 146 extends down through registering holes in the two members 141 and 143 and projects upwardly in the cup 141 outside of the deflector 145 almost to the top of the former.

50 A vertical passage 151 extends down through the casting 125 in register at its upper end with holes through the parts 141 and 143 so that it is in communication with the interior of the cup 141, all as is clearly shown in Figure 1.

55 The lower portion of the chamber 130 in the casting 125 is connected to the passage 151 by an inclined port 152 designed to be opened and closed by an inclined valve 153 loosely mounted in the end portion of a horizontal, tilted, bi-metal thermostat 154 secured near its other end at 155 by an adjusting screw to a sloping boss 156 forming part of the casting.

60 The inclination or tilt of the thermostat is for the purpose of facilitating its mounting on the casting.

A pipe or tube 157 connects the lower end of passage 151 to the interior of a pump casing 158 accommodating a vane pump 159 rotated in any approved manner preferably by power derived from the engine itself, such casing 70 having a discharge connection 161 delivering to the engine crank-case or other part of the lubricating system, whereby the reclaimed oil will be returned to such crank-case or system.

The connection 161 contains a ball check-valve 162 adapted under certain conditions to close the port joining the pump casing with the connection.

The operation of the appliance occurs practically as follows, assuming that the engine is 80 comparatively cold and is just being started.

The suction of the engine intake-manifold, acting through the pipe 127, passage 126, the separating or distillation chamber 130, passage 124, tube 123, cylinder-port 113, and 85 longitudinal channel 121, withdraws the aerated, more or less frothy or foamy oil from the lower piston-ring groove 116 behind the piston-ring 119, the air admitted through the port 122 being for the purpose of breaking 90 the vacuum to effect an efficient delivery of the oil from the groove and to aerate the oil so that it may be more readily purified in the distillation chamber.

This suction not only withdraws the excess 95 oil in aerated condition but it also draws off with the lubricating oil any intercepted gases of combustion, vapors, and fuel in gaseous or liquid form tending to pass down by the piston rings into the crank-case, whereby the 100 oil entering the distillation chamber incorporates gases and gasifiable contaminating ingredients which it is desired to get rid of because they would seriously impair the lubricating qualities of the oil if they were permitted to find their way into the crank-case.

Hence this appliance prevents the main body of lubricating oil in the crank-case from becoming fouled by the descent thereinto of 110 objectionable gases or liquids tending to escape past the pistons and it also precludes any excess oil from passing upwardly by the piston-rings into the combustion chambers where it would produce objectionable carbon.

The engine being cool on starting, the thermostatic valve 153 closes the oil delivery port 152.

The impure aerated oil enters the chamber 130 through the port 124 beneath the deflector 143 and the free air, gases and vapors 120 flow up through the pipe 146, then down in the cup 141 between the wall of the latter and the smaller inverted cup 145, then up in the latter, and thence down through the pipe 144, passage 126 and pipe 127 into the intake manifold for consumption or combustion in the engine, all as will be readily understood.

Any small amount of entrained oil in such gases is thrown down in the cup 141, by reason 130 of the tortuous path travelled by the gases,

and flows out through passage 151 and pipe 157 to the pump 159.

The main body of oil, however, is deflected into and collects in the lower part of the 5 chamber 130, and, as the engine heats up and heats the shell 128 by its hot exhaust gases, the oil builds up or accumulates in the annular space between the members 128 and 141, where it is adequately heated to distill off its 10 gasifiable ingredients which are drawn over into the intake-manifold, and the oil flows over into the cup 141 from which it passes down into the pump.

As soon as the engine and separating chamber 15 have become heated sufficiently so that the oil itself is hot enough not to require heating in the distillation chamber, the thermostat—immersed in the hot oil—will open port 152 thus affording a direct oil-delivery connection between the lower part of chamber 20 130 and the oil delivery pipe 157 and the accumulated oil immediately drains out through this connection.

As a result, the oil does not thereafter flow 25 up through the annular space between the members 128 and 141 and, consequently, it is not materially additionally heated in the chamber.

Such a construction and mode of operation 30 eliminates the possibility of the formation of objectionable carbon by reason of the performance of the oil rectification or distillation operation.

The reclaimed or purified oil flowing down 35 the pipe 157 enters the pump and the latter discharges it back into the engine crank-case or other part of the lubricating system under atmospheric pressure, it being obvious, that, owing to the differences in pressure in the 40 separation or distillation chamber and in the crank-case, such a pump or its equivalent, is necessary to effect the discharge against the higher pressure.

The pump should be of a capacity to return 45 without delay the maximum quantity of oil which would be delivered into the separating chamber under any running conditions of the engine, but it should not pump gases back into the lubricating system.

If the pump delivers its oil into the crank-case below the level of the surface of the oil therein, the crank-case oil itself will form a proper seal for the pump under all ordinary

conditions, but if the pump delivers its oil to the crank-case above the oil level therein, 55 then when the amount or quality of oil passing through the pump is incapable of keeping the latter constantly sealed, or when the pump is unduly worn, or when the engine is first started and no oil seal is available, the 60 check-valve 162, by closing, prevents air under atmospheric pressure from passing reversely through the pump from the crank-case and interfering with or destroying the 65 vacuum in the distillation chamber or pump intake connection 157, and hence preventing the delivery of the oil into the pump.

Thus it will be perceived that the aerated 70 impure or polluted oil is continuously withdrawn from around the engine pistons so long as the engine is running and the oil, as soon as reclaimed or freed from its gasifiable 75 impurities, is fed back to the lubricating system of the engine without delay or interruption or intermediate storage.

This invention is not limited to the particular embodiment thereof illustrated and described since other structures having its attendant advantages fall within the purview of the invention as defined by the appended claim.

I claim:

The combination of a rectifying-chamber, means connecting said chamber to the lubrication system of an internal-combustion engine, means to subject said chamber and connecting means to suction to withdraw impure lubricant from said system, to deliver such lubricant into said chamber, to facilitate the lubricant purifying process therein, and to withdraw the separated gases and vapors from the chamber, a pump to return the lubricant purified in said chamber under normal operating conditions substantially-immediately after its reclamation to the lubrication system of the engine under substantially atmospheric pressure, said pump having material capacity only for delivering liquids from said chamber to the system, and a check-valve associated with said pump to prevent interference with the sub-atmospheric condition in its intake whereby a lubricant seal is maintained in the pump.

In witness whereof I have hereunto set my hand.

RALPH L. SKINNER.
